UNITED STATES PATENT OFFICE.

ELMER K. COLE, OF WINTERSET, IOWA.

EARTH ANCHOR.

Application filed July 12, 1927. Serial No. 205,128.

The object of my invention is to provide a cable anchor of simple, durable and inexpensive construction, which may be formed of stock material.

More specifically it is the object of my invention to provide a cable anchor having comparatively few parts, the anchoring device being formed of sheet metal to greatly reduce the weight of the anchor without materially decreasing its strength, and at the same time increasing its efficiency.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is a side elevation of my invention providing cable anchor showing the manner in which it is placed in a suitable opening in the ground.

Figure 2 is a side elevation showing the manner in which the anchoring device is expanded, in its normal anchoring position.

Figure 3 is a detail, longitudinal, sectional view of the anchor.

Figure 4 is a perspective view of a double anchor supported on a single rod.

Figure 5 is a slightly modified form.

The numeral 10 indicates the anchor rod having an eye 11 at its upper end, and its lower end provided with screw threaded portion 12. The anchor comprises spaced head members 13, which are preferably formed of malleable iron or steel. Each end of the head 13 is provided with an inwardly extending anchoring plate 14. The upper ones of the members 14 are provided with slots 15 for receiving tongues 16 of the lower members 14, in the manner clearly illustrated in Figures 1 and 3. The head members 13 are each provided with a reinforcing plate 17. The said reinforcing plates and head members are provided with central openings 18 for receiving the threaded portion of the rod 12. The threaded portion of the rod 12 is provided with a nut 19, which prevents upward movement of the upper one of the head members 13, while the lower end of the rod 12 is provided with a nut 20 for engaging the lower head member 13. The lower reinforcing plate 17 is provided with an opening for receiving said nut, and outwardly extend-

ing flanges 21 for preventing the nut from rotating relative to the reinforcing plate and its adjacent head member. A spacing sleeve 22 is slidably mounted on the portion 12 between the head members 13, and limits the inward movement of said head members as they are drawn together.

In actual practice the anchor is assembled as shown in Figure 3, then placed in a hole 23 in the ground. After the anchor has been placed in the hole 23, which is slightly larger than the distance between the inner ends of the members 14, the anchor is temporarily supported against rotation by any convenient means at hand, after which the rod 10 is rotated, which will cause the nut 20 to be moved inwardly and the head members 13 to be moved toward each other. This in turn causes the free ends of the members 14 to be moved outwardly and to be pressed into the walls of the hole 23 in the manner illustrated in Figure 2. This operation is continued until the head members 13 engage the ends of the sleeve 22, which is for the purpose of preventing the anchoring plates from completely collapsing, in which case the strength of the anchor would be greatly reduced, as has been found by actual experiment. The hole 23 may then be tamped full of dirt or any other suitable material, after which the anchor is ready for use.

It will be seen that as the anchoring plates 14 are moved from the position shown in Figure 1 to the position shown in Figure 2, the metal at the intersection of the head member 13 and the anchors 14 will be bent to a straightened position. A certain amount of energy is required to perform the straightening of the plates. I find in smaller anchors that the amount of power required to straighten the plates at this point is negligible. In cases where heavier plates are used, then it is desirable to hinge the anchor members to the head members, in the manner illustrated in Figure 5. Each of the head members 13^a has one end provided with a slot 24 and the other end provided with a tongue 25. The slot in the upper head member is positioned opposite to the slot of the lower head member. Each of the anchor plates 14^a is provided at one end with a slot 26 and its opposite end with a tongue 27. The slot 26 of one of the members 14^a is placed over the tongue 25

of the head member 13^a, while the tongue 27 of said anchor plate is placed in the slot 26 of another one of the anchor plates 14^b, and the tongue 27 of the member 14^b is placed in the slot 24 of the upper head member 13^a.

By this arrangement it will be seen that all of the anchor plates are alike, as well as both head members 13^a, so that but a single set of dies is required to make all of the anchoring plates, and another set of dies to make the head members. This modified form of my device is operated the same as the preferred form.

15 In Figure 4 I have shown a slightly modified form of Figures 1 and 3, in which an extra set of head members and anchoring plates are placed on the rod 12, one set at right angles to the other, in the manner 20 clearly illustrated, thereby providing means whereby a double amount of anchorage may be obtained if so desired. This is sometimes desirable when the anchor is used in comparatively soft ground.

25 Thus it will be seen that I have provided a cable anchor which is constructed entirely of stock metal. The head members and anchor plates are formed of a bar of sheet metal of the proper width and thickness, 30 which is cut into sections and then bent into shape, making a very strong and efficient anchor, and at the same time comparatively light.

Considerable advantage is gained in lightening the weight of the anchor, which decreases the actual cost of construction, as well as decreasing the expense of shipping and handling. By providing the reinforcing plates 17, the head members are strengthened 40 to overcome the weakness caused by forming the openings 18, the reinforcing plates being preferably spot welded in position on the head members.

When the device is expanded to the position shown in Figure 2, a very strong and effective anchor is provided. The upper one of the head members, together with its co-acting anchor plate, gives the proper anchorage area, to carry the pulling strain of 50 the rod 10. The lower one of the head members together with the sleeve 22 imparts the strain to the upper head member from the rod 12 through the nut 20. The outer ends of the upper anchor plates are supported and carried by the lower anchor plates.

Considerable advantage is also gained by permitting the ends of the upper anchor plates to incline downwardly, so that the anchor has a tendency toward wedging the

dirt outwardly from the shaft 10, rather than in a line parallel with the said rod 10.

I claim as my invention:

1. A cable anchor comprising a pair of spaced head members, each provided with a central opening, one of said head members being provided with an opening at each end and the other with a tongue at each end, a series of hinge plates having comparatively thin ends, each of said plates having at one end an opening and at its opposite end a tongue, the openings of a pair of said plates being designed to receive the tongues of one of said head members while the other openings of the other head member are designed to receive the tongues of another pair of hinge members, said hinge members being mounted to normally project inwardly, the tongue of one of the inner ends of the corresponding plates being designed to enter an opening of the adjacent end of the other corresponding plate, an anchor rod having one end screw threaded and extending through the openings of said head members, and nuts on said screw threaded portion to force said head members inwardly toward each other and the inner connected ends of said plates transversely as the anchor rod is rotated.

2. A cable anchor comprising a pair of spaced head members, each provided with a central opening, one of said head members being provided with an opening at each end and the other with a tongue at each end, a series of hinge plates having comparatively thin ends, each of said plates having at one end an opening and at its opposite end a tongue, the openings of a pair of said plates being designed to receive the tongues of one of said head members while the other opening of the other head member is designed to receive the tongues of another pair of hinge members, the said hinge members being mounted to normally project inwardly, the tongue of one of the inner ends of the corresponding plates being designed to enter an opening of the adjacent end of the other corresponding plate, an anchor rod having one end screw threaded and extending through the openings of said head members, nuts on said screw threaded portion to force said head members inwardly toward each other and the inner connected ends of said plates transversely as the anchor rod is rotated, and a reinforcing plate adjacent to the outer surface of each of the head members for reinforcing the same.

ELMER K. COLE.
